UNITED STATES PATENT OFFICE.

ALLEN T. JOHNSTON, OF DORMONT, PENNSYLVANIA, ASSIGNOR TO THE UNION SWITCH & SIGNAL COMPANY, OF SWISSVALE, PENNSYLVANIA, A CORPORATION OF PENNSYLVANIA.

CONTROL AND INDICATION OF RAILWAY SWITCHES.

Application filed September 14, 1926. Serial No. 135,380.

My invention relates to railway switches, and has for an object the provision of apparatus for the control and indication of a switch from a distant point with a minimum 5 number of line wires between such point and the switch.

I will describe one form of apparatus embodying my invention, and will then point out the novel features thereof in 10 claims.

The accompanying drawing is a diagrammatic view showing one form of apparatus embodying my invention.

Referring to the drawing, the reference 15 character A designates a railway switch having the usual normal and reverse positions, the switch being shown in the normal position in the drawing. The switch is operated by a fluid pressure motor M, comprising a cylinder 1 and a piston 2 operating in the cylinder and connected with the switch A through a suitable mechanism indicated by the dotted line 3. The supply of fluid pressure to the cylinder M is controlled by 20 two magnet valves N and R arranged when energized to move the switch to its normal and reverse positions, respectively. The magnet valve N when energized admits fluid pressure from a suitable source through the 25 pipe 4 and the pipe 5 to the lower end of the cylinder 1, and when this valve is de-energized it disconnects the pipe 4 from the pipe 5 and opens the pipe 5 to atmosphere. Similarly, when the valve R is energized 30 it admits fluid pressure from the pipe 4 through the pipe 6 to the upper end of cylinder 1, and when this valve is de-energized it disconnects pipe 4 from pipe 6 and opens pipe 6 to atmosphere.

40 The magnet valves N and R are controlled by a manually operable circuit controller L located at a distant point, and the positions of the switch are indicated at such distant point by two electric lamps B^N and B^R, corresponding respectively to the normal and reverse positions of the switch. These lamps are controlled jointly by the circuit controller L and by a contact 14 operatively connected with the switch. The circuit controller L has normal and reverse positions, corresponding to the normal and reverse 45 positions of the switch, and as shown in the drawing, this circuit controller is in its normal position.

The operation of the apparatus is as follows: As illustrated in the drawing, lever L and switch A are both in the normal positions, and the normal magnet valve N is energized by a circuit which passes from the positive terminal of battery C, through 55 wires 9 and 10, contact 8 of circuit controller L, wires 11 and 12, magnet of valve N, asymmetric unit 20, and wire 13 to the middle point of battery C. Magnet N is, therefore, energized to hold the switch A in the normal 60 position. The normal indication lamp B^N is energized by a circuit which passes from the middle point of battery C, through wire 13, asymmetric unit 22, contact 14, wire 15, contact 7, lamp B^N, and wires 16 and 17 to the 65 negative terminal of battery C. In order to reverse the switch A, the operator moves the lever L to its right-hand position, whereupon a circuit for magnet valve R is closed, which circuit passes from the positive terminal of battery C, through wires 9 and 18, contact 7, wires 15 and 19, valve of magnet R, asymmetric unit 21, and wire 13 to the 70 middle point of battery C. Inasmuch as magnet valve R is now energized and magnet valve N is de-energized, the switch is shifted to its reverse position, and this in turn reverses the position of contact 14. The reverse indication lamp B^R will then become lighted through a circuit which passes 75 from the middle point of battery C, through wire 13, asymmetric unit 22, contact 14, wire 11, contact 8, reverse indication lamp B^R, and wire 17 to the negative terminal of battery C. In order to restore the switch to 80 the normal position, the operator reverses lever L to its normal or left-hand position, whereupon magnet valve R will become de-energized and magnet valve N will become 85 energized through the circuit which was traced hereinbefore. After switch A returns to its normal position, the normal indication lamp B^N will become lighted by virtue of the circuit which was likewise 90 traced hereinbefore.

100 Each of the asymmetric units 20, 21 and 22 is arranged to conduct current freely in the direction indicated by the arrow but not in the other direction. Each of these units may, for example, be of the type disclosed 105 and claimed in United States patent application, Serial No. 1111, filed by Lars O. Grondahl on January 7th, 1925, although I

do not wish to be limited to any specific type of unit.

The parts are so adjusted that when a lamp B^N or B^R is connected in series with the magnet of valve N or valve R, the lamp will not receive enough current to cause it to be lighted.

One feature of my invention is the provision of means for controlling the switch 10 and indicating its position over the same set of line wires without sacrificing any elements of safety.

Although I have herein shown and described only one form of apparatus embodying my invention, it is understood that various changes and modifications may be made therein within the scope of the appended claims without departing from the spirit and scope of my invention.

20 Having thus described my invention, what I claim is:

1. In combination, a railway switch having normal and reverse positions, means for operating said switch including a normal 25 magnet and a reverse magnet, a contact actuated by said switch, a manually operable circuit controlling lever having normal and reverse positions, a normal indication lamp and a reverse indication lamp, a circuit for 30 said normal magnet including a normal contact of said lever and a first asymmetric unit, a circuit for said reverse magnet including a reverse contact of said lever and a second asymmetric unit, a circuit for said 35 normal lamp including a normal contact of said lever and a third asymmetric unit and

said switch-actuated contact when in normal position, and a circuit for said reverse lamp including a reverse contact of said lever and said third asymmetric unit and said switch- 40 actuated contact when in reverse position.

2. In combination, a railway switch having normal and reverse positions, means for operating said switch including a normal magnet and a reverse magnet, a contact actuated by said switch, a manually operable circuit controlling lever having normal and reverse positions, a normal indication lamp and a reverse indication lamp, a source of direct current, a circuit passing from the 45 positive terminal of said source through a normal contact of said lever and the normal magnet and an asymmetric unit to an intermediate point of said source, a circuit passing from the positive terminal of said source 50 through a reverse contact of said lever and the reverse magnet and a second asymmetric unit to an intermediate point of said source, a circuit passing from an intermediate point in said source through a third asymmetric 55 unit and said switch-actuated contact when in normal position, and a normal contact of said lever and the normal indication lamp to the negative terminal of said source, and a circuit passing from the intermediate 60 point in said source through said third asymmetric unit and said switch-actuated contact when in the reverse position and said reverse indication lamp to the negative 65 terminal of said source. 70

In testimony whereof I affix my signature.

ALLEN T. JOHNSTON.
